AUTOMATIC WEFT REPLENISHING LOOM

George A. Litchfield, Jr., Ridgewood, N. J., assignor to Forstmann Woolen Co., Passaic, N. J., a corporation of New Jersey

Application September 11, 1953, Serial No. 379,687

18 Claims. (Cl. 139—232)

The present invention relates to looms and more particularly to apparatus for use in a well-known and widely employed type of loom for weaving textile materials whereby such loom may be adapted for automatic weft replenishment by changing bobbins while continuously weaving patterns of widely varying type including those requiring alternating pick and pick weaving with two or more shuttles.

It will be recognized that the principles of the present invention may be embodied in structures variously designed for use in many types of looms. For the purpose of illustration the present invention has been shown embodied in a Crompton & Knowles Type W-3 convertible loom provided with the sliding pick motion, tricolor attachment and magazine customarily furnished by the manufacturer for various conversions of that loom and in addition provided with an A. & W. filling feeder attachment of the type shown in U. S. Patent No. 2,399,457. In accordance with the present invention, the latter features have been adapted to function in combination with a new form of shuttle box and revoker mechanism to provide great flexibility in operation of the loom.

An important feature of the present invention is the provision of a shuttle box at the magazine end of the loom having two or more cells which are stacked vertically and are movable as a unit in response to the box pattern chain to position any desired one of such cells at race plate level. Means are provided for moving the uppermost cell of said shuttle box independently of the remaining cell or cells therein to space said upper cell vertically away from the next lower cell by a distance sufficient to permit ejection of an exhausted quill. Such independent movement of the upper cell occurs only when a transfer cycle has been initiated. The separation of the upper cell from the next lower cell makes it possible to transfer whether or not there may be a shuttle in the next lower cell. Preferably an automatically operating chute is provided between the upper cell and the next lower cell which may be so positioned upon separation of the cells as to deflect an exhausted quill in a generally horizontal direction from the space between said separated cells.

Another important feature of the present invention is a revoker mechanism controlled by the head motion which may be employed with great advantage in many forms of looms. When employed in conjunction with the special shuttle box also provided by the present invention it is possible to weave automatically a great variety of patterns which heretofore could be produced on looms of this general type only when manual weft replenishment was practiced.

Ordinarily when a loom of the general type referred to above is converted for straight, automatic operation, a two-cell shuttle box is used at the drive or magazine end of the loom. Detection occurs on alternate picks. Thus as the lay moves toward front center in one pick in which a shuttle enters the uppermost cell of such shuttle box, the feeler of a detector mechanism is brought

2

into engagement with the bobbin in such shuttle. If the detector indicates that transfer is necessary, transfer may occur two picks later provided the same shuttle returns to the upper cell at such time, and further provided there is no shuttle in the lower cell. The latter condition is necessary because the exhausted quill must be ejected through the empty lower cell. Also, it is necessary that transfer occur when the lower cell is at race plate level. Thus in building a box pattern chain for such operation, it is necessary to move the shuttles in a particular sequence which excludes the possibility of alternating pick and pick weaving.

In contrast with this the present invention provides detection on each pick and a shuttle box having two, three, four or more cells on the magazine end of the loom, the uppermost one of which may be split away from the next lower cell for transfer. This novel shuttle box combined with the novel revoker mechanism for preventing transfer at any inappropriate time, provides a box pattern chain cycle of relatively low number of picks in which every shuttle in use may be detected in one pick and replenished if necessary in the next pick. With such arrangement it will be apparent that alternating pick and pick weaving may be accomplished with substantially any desired number of shuttles in use.

It is the object of the present invention to provide a loom having the great flexibility described above which shall be simple and reliable in operation and provided with certain structural features described in detail hereinbelow.

Referring now to the drawings, there is shown a preferred, but not necessarily the only form of the present invention. The drawings also include diagrams illustrating the operation of the preferred and several modified forms of the invention.

In the drawings:

Fig. 27 is a diagrammatic view showing the relative positions of the shuttles and shuttle boxes in an 8-pick cycle of operation of a loom embodying the present invention and in which two shuttles are used in alternating pick and pick operation and in which two shuttle box cells are used at both ends of the loom;

Fig. 28 is a diagrammatic representation of a box pattern chain arranged for operation as illustrated in Fig. 27;

Fig. 29 is a diagrammatic view showing the relative positions of the shuttles and shuttle boxes in a 24-pick cycle of operation of a loom embodying the present invention and in which four shuttles, each having a different color, are used in a 3 x 3 operation in a 4 x 4 loom in alternating pick and pick sequence;

Fig. 30 is a diagrammatic illustration of the box pattern chain arranged for operation as illustrated in Fig. 29;

Figs. 31 and 32 are diagrammatic views showing the relative positions of the shuttles and shuttle boxes in a 56-pick cycle of operation of a loom embodying the present invention and in which 7 shuttles, each having a different color, are used in a 4 x 4 operation in a 4 x 4 loom in alternating pick and pick sequence; and

Fig. 33 is a diagrammatic representation of the box pattern chain arranged for operation as illustrated in Figs. 31 and 32.

Referring first to Fig. 1, there is shown the major conventional parts of a Crompton & Knowles W-3 convertible loom arranged for 4 x 4 manual operation insofar as the convertible feature of the loom, as furnished by the manufacturer, is concerned. A four-cell shuttle box of the construction ordinarily used with such a loom in such an arrangement may be used at the head end of the loom when it is modified in accordance with the present invention. However, a shuttle box of special construction having certain novel motions is provided at the drive end of the loom for the purpose of making the loom capable of fully automatic pick and pick weaving, for example, wherein weft replenishment is accomplished by automatic changing of quills or bobbins. The special shuttle box may be used at both ends of the loom to give even greater flexibility as will be explained hereinbelow. Certain modifications have been made in various parts of the loom to provide the special motions required and to adapt it to effect proper color selection

and to prevent quill changes at inappropriate times. While the present invention has been illustrated in conjunction with a specific commercially available loom, it will be understood that it is not limited to use with such loom and that the principles of the present invention may be applied to looms of various standard or special constructions.

As shown in Fig. 1, the loom is provided with a main frame comprising legs 10 and arch 12. The major operating parts of the loom are assembled upon the framework and include the lay assembly, indicated generally at 14, and the head motion assembly, indicated generally at 16, which is carried on the head motion frame 18 forming a part of the arch or upper section 12. The loom is provided with the usual harnesses 20 and reed 22. The main shaft 24 and crank shaft 26 are mounted for rotation in the frame for driving the principal components of the loom and for moving the lay in a well-known manner.

10 20 A four-cell shuttle box 28 of conventional box-loom construction may be provided at the head end of the loom and is mounted for vertical movement to position any one of the four cells thereof level with the race plate 30. The shuttle box 28 may be moved to these 25 various positions by a conventional box lifting mechanism, indicated generally at 32, under the control of a box pattern chain indicated generally at 34. At the drive end of the loom a similar box lifting mechanism 36 is provided for elevating the shuttle box positioned 30 at that end of the loom. In accordance with the present invention, a four-cell shuttle box indicated generally at 38 is of special construction as will be described in detail hereinbelow. The special shuttle box 38 has the 35 normal vertical motions imparted thereto by the box lifting mechanism 36, under the control of the box pattern chain 34, to position a desired cell at race plate level.

The loom shown in Fig. 1 is also provided with a magazine 40 which, for purposes of illustration, is shown as 40 the type of magazine which may contain up to four separate sets of quills from which any desired quill may be selected by the mechanism to be described hereinbelow. It will be understood, however, that the present invention is not specifically limited to cooperation with 45 the particular magazine herein illustrated, and furthermore, that the principles of the present invention are equally adaptable to constructions wherein cops, shuttles or other forms of replaceable units may be positioned in 50 a shuttle box upon exhaustion of a unit which has heretofore been in use.

Picker sticks 42 and 44 are shown respectively at the drive and head ends of the loom and these may be actuated by any suitable mechanism, as for example, the 55 sliding pick mechanism which will be described hereinbelow.

In addition to the conventional major components of the loom chosen for illustration herein, Fig. 1 shows certain parts which have been added thereto to embody the 60 present invention. Thus the head motion 16 is provided with additional parts for the actuation of a revoker linkage, indicated generally at 46, and a color selector linkage, indicated generally at 48. The revoker linkage 46 is provided to prevent operation of the transfer mechanism at any inappropriate time. The color selector linkage 48 is provided for the selection of a quill from the proper cell of the magazine 40 whenever a transfer 65 is to be effected. The detector cam indicated at 50 in Fig. 1 has been redesigned in accordance with the present invention to provide a complete cycle of operation of the detector mechanism upon each pick whereas the particular type of loom herein illustrated normally provided a complete cycle of operation of the detector mechanism on every other pick. In this connection it should be 70 pointed out that the main shaft 24 performs one com-

plete revolution for each two revolutions of the crank shaft 26 and thus there will be two picks during each complete revolution of the main shaft 24.

The special shuttle box 38 provided in accordance with the present invention must have at least two cells and as illustrated includes four cells numbered from the top down, as is customary in the loom art. Cell #1 of the box 38 is mounted for movement as a unit with cells #2, #3 and #4 in response to the normal operation of the box lifting mechanism 36 during the weaving operation. However, cell #1 of the box 38 is also mounted for vertical movement relative to cells #2, #3 and #4 so as to provide a space between cell #1 and cell #2 through which an exhausted quill may be ejected. One feature of the present invention lies in the provision of a collapsible chute which normally lies flatwise between cells #1 and #2 and which moves into an inclined position therebetween when cell #1 is moved away from cell #2. Such collapsible chute will be described in detail hereinbelow. The provision for separation between cells #1 and #2 and the positioning of the chute therebetween makes it possible to effect transfer even though cell #2 is to receive a shuttle or has a shuttle therein which will be sent therefrom during the time that transfer must occur. It will be readily recognized that this ability will vastly increase the flexibility of the loom. As will be described hereinbelow, the present invention makes it possible to effect alternating pick and pick weaving with fully automatic weft replenishment with as few as two shuttles or as many as seven shuttles in a 4 x 4 arrangement or even a greater number of shuttles if five or more cells were to be provided in the shuttle boxes at both ends of the loom.

The revoker mechanism referred to briefly above is arranged to prevent cycling of the transfer mechanism at all times except those in which a particular shuttle will remain in cell #1 of box 38 during at least the latter part of one pick and the early part of the next pick. It will be understood that in the design of the box pattern chain for any particular fabric it will thus be necessary to provide at least one instance in which each shuttle may remain in cell #1 of box 38 during at least the latter part of one pick and the early part of the next pick, and for the second such pick it is essential that the box 38 be moved to a particular level with respect to the race plate in order that cell #1 will be properly positioned with respect to the magazine to receive a new quill.

For purposes of illustration, the present apparatus has been disclosed in a form wherein cell #2 of box 38 must be positioned level with the race plate at the time a transfer is made, although as will be apparent transfer can be effected with the box 38 at any other level by suitable repositioning of the magazine 40. Proper vertical positioning of the magazine may be conveniently achieved by the provision of any one of a series of spacers 52. The spacer 52 illustrated in Fig. 1 positions the magazine 40 for cooperation with cell #1 when it is separated from cell #2 and when cell #2 is at race plate level. In the event that all four cells of box 38 are used, a different spacer will be provided which raises the magazine a distance equal to the depth of one cell so that transfer may be effected with cell #3 at race plate level. While transfer could be effected with other cells at race plate level, it has been found as a practical matter that the two positions thus described are adequate for operation under any set of conditions which may be found desirable with the 4-cell boxes herein illustrated.

Referring now to Figs. 2 through 5, there is shown a mechanism for operating the revoker and color selector linkage referred to above. Such mechanism is actuated by a box pattern chain and consists of special vibrator levers. The chain shown in Fig. 5 and indicated generally at 56, is constructed for two-color pick and pick weaving with two shuttles in a 2 x 2 box arrangement. The box pattern chain normally used in a loom such as

that chosen for illustration herein is made up of bars which provide five longitudinally extending lines in which risers and sinkers may be positioned to actuate the vibrators for controlling box motion and such other motions as may be desired, dependent upon the particular conversion within the capacity of that loom. For the purposes of the present invention the box pattern chain has been altered to provide space for additional lines of risers and sinkers to control additional motions made necessary by this invention. Thus while the particular chain illustrated in Fig. 5 has five spaces between the links, bars of extra length have been employed so that additional risers or sinkers may be placed outside the links. The chain shown in Fig. 5 thus provides seven spaces for seven lines of risers and sinkers, four of which are used to control box motion at the drive and head ends, one for sliding pick motion, one for color selection and one for control of the revoker. The color selection and revoker lines are shown towards the ends of the bars outside of the chain links to minimize modifications in the head motion of the loom. Two additional vibrators have been provided which operate in vertical planes lying outside the normal width of the chain and which cooperate with the risers or sinkers placed near the ends of the chain bars.

The color selector vibrator thus provided is identified by the reference numeral 58 (see Figs. 2 and 3). The vibrator 58 is pivoted at one end to the heel pin 60 and at its free end is connected to a chain 62 which passes around an idler 64 and is, in turn, connected to an arm 66 of a bell crank pivoted at 68 to the head motion frame 18. The other arm 70 of this bell crank is provided with a slot 72 to receive a stud 74 secured to the end of the color selector linkage 48. The stud 74 may be secured within the length of the slot 72 at different distances from the pivot 68 to provide such length of stroke for the linkage 48 as may be desired. The vibrator 58 is provided near the heel pin end with a shoe 80 which is positioned in the path of the risers or sinkers of the box chain 56. It will be apparent that the varying distances through which the shoe 80 may be moved by the risers or sinkers on the chain 56 will be reflected in proportionate lengthwise movement of the color selector link 48.

The revoker vibrator 82 (see Figs. 2 and 4) is constructed similarly to the color selector vibrator 58 just described and is provided near the heel pin end with a shoe 84 for cooperation with appropriate risers and sinkers on the box pattern chain 56. Near its free end the vibrator 82 is connected through a flexible chain 86 with a bell crank lever 88 to which the revoker linkage 46 may be adjustably secured. The mechanism just described provides for lengthwise movement of the revoker linkage 46 proportionate with vibrator movement imparted by the box pattern chain.

As stated above, the special vibrators 58 and 82 are actuated by risers and sinkers which, for convenience, have been positioned outside the links of the box pattern chain. Referring now to Fig. 5, the chain 56 is made up of a plurality of bars 90 and links 92. The bars 90 are of such length as to accommodate near the left hand ends thereof, as viewed in Fig. 5, a series of risers or sinkers of various diameters for the purpose of selecting any one of a desired number of colors. The particular chain shown in Fig. 5 provides for the selection of any one of two colors as called for by a series of sinkers 94 and risers 96. Where more than two colors are to be selected, an appropriate assortment of risers of various diameters will be provided.

The bars 90 extend beyond the links 92 on the right hand side, as viewed in Fig. 5, for a distance sufficient to accommodate risers 98 and sinkers 100 which control the motion of the vibrator 82 which operates the revoker linkage as described above. Since the revoker mechanism requires only two positions, it has been found convenient to use sinkers and full-sized risers. The risers

and sinkers positioned on the bars 90 between the links 92 may be arranged in any suitable manner.

The box motion vibrators are of conventional design and only one of them has been illustrated in Fig. 7. The vibrator 102 shown therein is positioned for co-operation with risers 104 and sinkers 106 on the box pattern chain 56. The vibrator 102 serves to control the position of cells #1 and #2 of the box 38. The vibrator 102 is pivoted on the heel pin 60 and at its free end carries a vibrator gear 107 forming a part of the familiar Crompton & Knowles head motion. A vibrator connector 108 is coupled with a lever 110 pivoted at 112 and connected intermediate its length with a flexible chain 114. The chain 114 passes around an idler sprocket 116 which may be moved bodily in relation to the pivot 112 by the vibrator connector 118. Such motion of the sprocket 116 alters the length of stroke of the chain 114 in response to movement of a vibrator (not shown in Fig. 7) which serves to position cells #3 and #4 opposite the race plate in any setup in which those cells must be moved to such position. It will be understood that the particular box pattern chain shown in Fig. 5 does not provide for movement of the idler sprocket 116 inasmuch as cells #1 and #2 only are positioned at race plate level in this particular pattern. The chain 114 is conducted over an idler sprocket 120 and is connected by means of a quarter-turn link to a chain 122 which, in effect, is a continuation of chain 114. The chain 122 passes over an idler sprocket 124 and as shown in Fig. 6, extends from the sprocket 124 to an idler sprocket 126 and from there the chain 114 passes over an idler sprocket 128.

Referring now to Fig. 1, the last-mentioned idler sprocket 128 may be seen beneath the lay end of the loom. The chain 114 then extends across the loom to an idler 130 beneath the shuttle box 38 and downwardly to engage a box lifter tube 132. The mechanism just described is conventional and it will be understood that lengthwise movement of the chain 114 imparted by the box pattern chain 56 will produce corresponding vertical motion of the box 38 in usual fashion.

As will be explained in greater detail hereinbelow the spacing between the floors of cells #1 and #2 of the shuttle box 38 is greater than the spacing between the floors of the remaining cells as a result of the interpositioning between cells #1 and #2 of the pivoted chute to which reference has been made. The mechanism for providing an appropriate additional vertical travel for the box lifting mechanism, whenever a shift is made between cells #1 and #2, is shown in Fig. 6.

In Fig. 6 the parts as shown in the position assumed when cell #1 of the box 38 is at race plate level. To assume this position the portion of the chain 114 between sprockets 124 and 126 has been moved downwardly to the maximum extent. The chain 114 thus will move upwardly to shift the box 38 to position any one of cells #2, #3 and #4 at race plate level. As explained above, the box 38 must move upwardly a somewhat greater distance to bring cell #2 to race plate level than it needs to move thereafter in bringing #3 and #4 respectively, to race plate level. To this end there is provided a pair of spaced idler sprockets 134 and 136 which are so positioned as to engage the links of chain 114 from one side. A mutilated idler sprocket 138 is positioned on the opposite side of the chain with its axis approximately midway between the axes of the idlers 134 and 136. The mutilated idler 138 is provided with a series of teeth 140 and a flat side 142. It will be observed that the chain 114 engages only two teeth 140 of the idler sprocket in the position of parts shown in full lines in Fig. 6 and that the path of the chain from idler sprocket 134 to idler sprocket 136 is shortened as a result of the position of the flat 142. When the chain moves upwardly to elevate cell #2 to race plate level, idler sprocket 138 will be rotated counter-clockwise toward the position shown in

broken lines in Fig. 6. In the latter position the chain 114 must follow the circular outline of the toothed portion of sprocket 138 and thus follow a longer path between the idlers 134 and 136. This results in a shortening of the effective overall length of the chain 114 with an attendant additional vertical displacement of the box 38. Further upward movement of the chain 114 incident to the positioning of cells #3 or #4 at race plate level will be accomplished without any change in length of the chain 114 since throughout such motions the chain engages the toothed portion of idler 138. Similarly, upon movement in the opposite direction to lower the box 38, the increments between cells #4, #3 and #2 will be equal wherever as the parts again approach the position illustrated in full lines in Fig. 6, the effective overall length of chain 114 will be lengthened to produce the desired additional vertical travel from cell #2 to cell #1 of box 38.

In Fig. 9 there is illustrated certain essential parts of the sliding pick motion embodied in the Crompton & Knowles convertible loom which has been chosen for illustration as a standard loom to which the present invention may be adapted. This conventional mechanism is operated in response to a series of risers or sinkers on the box pattern chain, specifically the risers 144 and sinkers 146 shown in Fig. 5 and the vibrator 148 shown in Fig. 8. When the vibrator 148 is elevated by a riser 144, as shown in Fig. 8, the sliding pick motion will be positioned to make a pick from the drive end of the loom. Fig. 9 is a rear elevational view and accordingly, the right hand portion of Fig. 9 corresponds with the head end of the loom. Also Fig. 9 shows the sliding pick motion in the position it assumes when a sicker 146 is in contact with the vibrator 148. That is, the position of parts shown in Fig. 9 does not correspond with the arrangement of risers and sinkers shown in Fig. 8. In the position shown in Fig. 9, the mutilated gear 150 has been moved to its lower position in which it receives counter-clockwise rotation thus rocking the vibrator connector 152 and lever 154 about the pivot 156 to raise the linkage 158 which rocks bell crank lever 160 about a pivot 162 mounted on a fixed arm 164. One arm of the bell crank lever 160 is provided with a pin 165 which engages an annular groove 166 in a collar 168 which serves to shift the picking arm 170 relative to a hub 172 fixed on the main shaft 24. As shown in Fig. 9, the picking arm 170 has been moved toward the right to a position wherein it will engage the picking shoe 174. A link 176 extends across the loom to cause corresponding movement of the picking arm 178 at the drive end of the loom. As shown in Fig. 9, the picking arm 178 has been moved toward the right into a position wherein it will not engage the picking shoe 180. When a riser 144 is positioned beneath the vibrator 148, the mutilated vibrator gear 150 will be rotated clockwise to a position 180° removed from that shown in Fig. 9 and the mechanism just described will be moved to cause engagement of the picking arm 178 with the picking shoe 180 at the drive end of the loom with a corresponding disengagement of the picking arm 170 and picking shoe 174 at the head end of the loom.

In Fig. 10 there is shown a double-lobed cam 50 for operating the detector mechanism as generally described above. This cam includes upper and lower halves 180 and 182 as viewed in Fig. 10, and each half produces a complete detecting motion. This motion is effected by movement of a follower roller 184 which rides within the cam track 186 and which is positioned at one end of a lever 188 pivoted at 190 to the frame of a loom. At its opposite end the lever 188 is provided with parallel slots 192 and 194. These two slots are provided by the manufacturer for conversion of the loom for 4 x 1 straight automatic operation or 4 x 2 filling mixing operation. For the purposes of the present invention, one or the other of the slots 192 and 194 will be used depending upon the number of cells of box

38 which it may be desired to put into operation and upon other factors, as will be apparent to those familiar with the art. As shown in the drawings, the detector rod 196 is engaged with the slot 194 for the particular operation chosen for first illustration herein.

The special shuttle box 38 with independently movable top cell provided in accordance with the present invention will now be described with reference first to Fig. 1. In Fig. 1 cell #1 of the box 38 is locked to the remaining cells of the box in the position which it normally assumes during the weaving operation. In this figure, cell #1 is positioned at race plate level and accordingly, the box 38 is in the lowest position which it assumes in operation. The box 38 is mounted for vertical movement in outer and inner box guides 198 and 200 respectively. The vertical motion referred to is imparted by the mechanism described above whereby the box lift tube 132 is moved vertically in response to shifting of the chain 114. The tube 132 is slidably upon the box rod 202 but a stiff give-away spring 204 is interposed between the tube 132 and locknut 206 fixed to the box 38. Vertical movement of the tube 132 is transmitted to the box 38 through the stiff spring 204 as is customary in loom construction. The spring 204 is provided to prevent injury to the mechanism in the event of a jam.

It will be noted that the magazine 40 is positioned at such a level that cell #1 would be in transfer position if cell #3 were to be elevated to race plate level, assuming that the split box remains in the locked position illustrated in Fig. 1. However, for the 2 x 2 operation chosen as the primary illustration, cell #3 does not rise to race plate level. Transfer occurs with cell #2 at race plate level and cell #1 split to the extent of approximately the depth of a cell so as to occupy transfer position. This provides a space through which an empty bobbin may be discharged in the course of transfer. In case it is desired to accommodate a particular number of shuttles which would require the use of cell #3, the magazine 40 may remain at the level illustrated in Fig. 1, and transfer will occur with cell #2 at race plate level, as will be explained hereinbelow. In case an even greater number of shuttles is to be accommodated, the magazine may be elevated by the use of a larger or additional spacer 52 which secures the magazine 40 in a position such as to accommodate the depth of one or more additional cells. The principles of the present invention are not restricted to any specific number of cells or to transfer with any particular cell at race plate level although for purposes of illustration, certain specific examples will be described in detail.

Referring now to Fig. 12, the split box 38 provided in accordance with the present invention is shown in detail and in the position which it assumes at the instant of transfer. Thus in Fig. 12, #2 cell is at race plate level and #1 cell has been split away from #2 cell and thus brought up to magazine level for the transfer operation. The uppermost position of cell #1 may be limited by a safety stop 201 secured to the box guide 200 in a position appropriate for the number of cells being used and the corresponding vertical position of the magazine 40. The lifter rod 202 and spring 204 have been omitted from this figure and there is shown only the additional mechanism provided for shifting of cell #1 relative to the other cells. Cells #2, #3 and #4 are shown as a three-unit construction of substantially conventional form and they are provided with the usual spring pressed shuttle binders 208, 210 and 212, respectively, which operate in the usual fashion. These three cells move as a unit in accordance with the box pattern chain. Cell #1 is constructed as a single unit separate from the other cells which rides vertically between the box guides 198 and 200 in much the same way as the remaining cells. As stated above, cell #1 may move jointly with or independently of the remaining cells in box 38. To this end cell #1 is provided with two bosses 214 and 216

5 in which are fixed, respectively, vertically disposed rods 218 and 220 slidably received in bosses 222 and 224 secured to the cell unit comprising cells #2, #3 and #4. At their lower ends the rods 218 and 220 are secured to a saddle 226. The saddle 226, rods 218 and 220 and cell #1 thus form a rigid rectangular frame which may be moved vertically within the bosses 222 and 224.

When cell #1 is lowered into engagement with cell #2, it is locked in that position by a pair of lock pawls 228 and 230 positioned at the opposite ends of a rock shaft 232 pivoted in suitable bearings 234 and 236 attached to the saddle 226. The rock shaft 232 has fixed thereon a lever 238 and a pair of spaced torsion springs 240 and 242 arranged to urge the shaft to rotate in such direction that the pawls 228 and 230 tend to move toward the cell unit comprising cells #2, #3 and #4.

A horizontally disposed lock knife 244 (see Fig. 13) is pivoted at 246 on the saddle 226 and is provided with an upturned plate 248 positioned for engagement with the lever 238 on rock shaft 232 (also see Fig. 12). Referring again to Fig. 13, the lock knife 244 has at its free end a square perforation to receive the upper end of a lock knife finger 250 which projects through a slot 252 in the saddle 226. The lock knife finger 250 (see Fig. 12) may slide freely through the perforation in lock knife 244 in the course of vertical movements of the shuttle box 38 while maintaining constant connection with the lock knife 244. At its lower end the lock knife finger is pivoted at 254 on a fixed part of the lay-end. As will be apparent from a consideration of Figs. 12 and 13, rocking of the lock knife finger 250 will be effective to swing the lock knife 244 in a horizontal plane to move the plate 248 relative to the lever 238 and thus to permit or cause rocking of the shaft 232 and the locking pawls 228 and 230. In the position shown in Figs. 12 and 13, the lock knife has thus been moved forward to withdrawn the pawls 228 and 230 from engagement with any part of the three-cell unit. As an incident to the lowering of cell #1 from the position shown in Fig. 12 into proper weaving relationship with cell #2, the mechanism just described will be actuated to permit the pawls 228 and 230 to swing backward whereupon they will engage the lower corner of the lowermost cell of box 38 as clearly shown in Figs. 21 and 25. The locking pawls 228 and 230 are each provided with a notch of suitable contour to firmly engage both the side and bottom wall of the lowermost cell and thus to hold cell #1 rigidly in the position shown in Fig. 21. When it is desired to unlock cell #1 for movement relative to the remaining cells in the unit, the locking finger 250 is moved forwardly as viewed in Figs. 12 and 13 to retract the pawls into the position shown in those figures.

55 Independent vertical movement of the cell #1 may be imparted by any suitable mechanism. A preferred form of mechanism is shown in the drawings which consists of a vertically disposed lifter rod 256 which extends through a boss 258 secured to a bracket 260 fixed on the lay-end 262. By mechanism which will be described, the rod 256 is reciprocated every cycle of the loom. The rod 256 extends freely through a boss 264 (see Fig. 16) secured on the saddle 226 and its upper end is provided with a step 266 (see Fig. 26) which moves from a position closely approximating the level of the top of saddle 226 at the lowermost end of the reciprocation of rod 256 to an elevated position illustrated in Fig. 26. Mechanism is provided for connecting the saddle 226 with the reciprocating rod 256 at such times as it might be desired to move cell #1 relative to the remaining cells. This mechanism is best shown in Figs. 13, 16, 25 and 26. In Figs. 13 and 16, the rod 256 is connected with the saddle 226 while in Figs. 25 and 26 it is disconnected. The means for effecting the connection includes the lock knife 244 (see Fig. 13) which has been described above. The lock knife is

11

provided with a notch 268 and the boss 264 is provided with a horizontal slot 270 (see Fig. 25) to receive the portion of lock knife 244 in which notch 268 is formed. When the lock knife 244 is moved forward to unlock the pawls 228 and 230 the notched portion 268 thereof will move through the slot 270 and into a position to overlie the step 266 in rod 256. Thus the next upward movement of the rod 256 will be transmitted to the saddle 226 and cell #1. As will be explained hereinbelow, the mechanism is so timed that the lock knife 244 will move into the position just described only when the vertically reciprocating rod 256 is in its lowermost position.

To move the lock knife 244 into the position in which it engages the vertically reciprocating rod 256 and serves to unlock the pawls 228 and 230, the mechanism shown in Fig. 24 is provided. In this figure the lock knife finger 250 is shown extending through a slot 252 in the saddle 226 and through the lock knife 244. The bracket 260 is provided with an opening 272 through which projects a link 274 connected at 276 with the lock knife finger 250 and at 278 with bell crank lever 280 pivoted at 282 on a bracket 284 secured to the lay end 262. The bell crank lever 280 is urged to rotate clockwise as viewed in Fig. 24 by a tension spring 286. Such clockwise rotation of the lever 280 serves to move the lock knife finger 250 to the right as viewed in Fig. 24 and this movement places the lock knife 244 in the position shown in Fig. 25. The bell crank lever 280 has connected to it a downwardly extending link 288 which is actuated by a mechanism to be described to move the lock knife 244 forwardly into operative position whenever the indicator mechanism of the loom operates to initiate a transfer.

Referring again to Figs. 12 and 13, it will be observed that the upper portion of lift rod 256 is rectangular in cross-section and that the boss 258 is provided with a rectangular bore 290 to receive the rod 256. The lower portion 294 of rod 256 is cylindrical. At the lower end of the boss 258 there is positioned a washer 292 having a circular opening to receive the cylindrical extension 294 which projects beneath the boss 258. At its lower end there is secured to the cylindrical extension 294 an offset collar 296. An expansive spring 298 is positioned between the collar 296 and the washer 292 and the expansive force of this spring assists gravity in urging the lift rod 256 downwardly. The offset collar 296 has secured to it an adjustable chain rod 300 connected with a flexible chain 302 which is conducted over idler sprockets 304 and 306 carried by the bracket 260 on the lay-end 262. At its opposite end the chain 302 is connected to a chain rod 308.

Referring now to Fig. 11, the chain rod 308 is connected with a short length of chain 310 which passes around an idler sprocket 312 and is connected by means of a chain rod 314 with the lower end of a lever 316 pivoted at 318 on a bracket 320 on the main frame of the loom. Intermediate its ends, the lever 316 carries a follower roller 322 which cooperates with a double-lobed cam 324 fixed upon the main shaft 24. Since the main shaft makes but one revolution for two cycles of the loom, the double-lobed cam 324 is necessary to provide a reciprocation of the lifting rod 256 for each cycle of the loom. The spring 298 described in the preceding paragraph maintains the chain linkage under tension and holds the follower roller 322 firmly in engagement with the face of the cam 324.

The adjustable chain rod 300 (see Fig. 12) provides for accurate positioning of the lift rod 256 so that the step 266 will be certain to fall below the level of the lock knife 244 in each stroke. The length of the stroke after engagement with the lock knife must be accurately predetermined and while controlled primarily by the shape of the cam 324, the final adjustment of the ultimate maximum lift is arrived at by adjusting the position of the

12

offset collar 296 on the cylindrical extension 294 of the lift rod 256. Obviously the cam 324 is so shaped and so positioned upon the main shaft 24 as to impart lifting motion to cell #1 at a precisely determined instant within the cycle of operation of the loom.

As will be apparent from the foregoing description, cell #1 is unlocked from and elevated relative to the remaining cells only at the time a transfer is to be made. At such times cell #1 is moved to a particular vertical position with respect to the magazine 40 as illustrated in Figs. 12 and 16. When transfer occurs a filled bobbin is projected from the magazine 40 into the shuttle in cell #1 and the exhausted bobbin is expelled from the shuttle by the incoming filled bobbin. This operation is carried out by a hammer which moves at very high speed and considerable force is exerted upon the shuttle and the cell in which it is positioned. Accordingly it is desirable to provide a substantial support for holding cell #1 steady during the transfer operation. In Fig. 19 a suitable support or steadier 325 is shown mounted upon the breast beam 326 (also see Fig. 17). Secured to the breast beam 326 is a bearing 328 which receives a shaft 330 on which is pivoted a lever 332 having a horizontal extension 334 threaded to receive a screw-threaded body 336 having an enlarged head 338 which is notched at 340 to receive the lower forward corner of cell #1. The lever 332 is constantly urged to rotate clockwise about the pivot 330 by a leaf spring 342 secured at 334 to the breast beam 326. Clockwise rotation of the lever 332 is limited by a set screw 346 threaded into a tail 348 formed on the lever 332. The set screw 346 adjustably engages the breast beam 326 to establish desired backward position of the steadier 325 in which it is ready to engage cell #1 as will be explained. The screw threaded body 336 may be rotated to position the notched head 338 in desired vertical relationship with cell #1 and may be held in adjusted position by a set screw 350.

Since the steadier 325 is mounted on the breast beam and cell #1 is carried by the lay, cell #1 will move toward and from the steadier on each cycle of the loom. Except when transfer occurs a binder retainer 352 or 354 on box 38 (see Fig. 12) will strike the steadier 325 and swing it idly forward. When cell #1 is elevated for transfer the lower front edge thereof will engage the steadier in operative relation. In the particular loom herein illustrated approximately 40° of the loom cycle are needed for transfer and this portion of the cycle is that in which the lay approaches, reaches and recedes from front center. Thus it is desirable that the box 38 steadier shown in Fig. 19 be so shaped and adjusted that it will be engaged by cell #1 approximately 20° ahead of front center and remain in engagement therewith until the lay recedes approximately 20° from front center.

When a transfer is to be made and cell #1 is elevated by the mechanism above described and has been brought forward into engagement with the steadier 325, the lifting mechanism for cell #1 may be disengaged so that cell #1 will return to normal position as soon as it is retracted from the steadier. To this end a stationary push finger 356 is mounted on the feeler housing (see Figs. 16, 17 and 23). The feeler housing or feeler stand to which the finger 356 is secured will be described in detail hereinbelow but it will be understood that it is a stationary part of the loom. Thus, movement of the lay is relative to the finger 356. Referring now to Fig. 23, the stationary push finger 356 is shown in its relation with the plate 248 on lock knife 244. Since these parts are carried by the saddle 226 they move backwards and forwards with the lay and they also move vertically with cell #1 when it moves independently of the remaining cells in box 38. In those instances wherein cell #1 is locked to the remaining boxes, the parts 244 and 248 will occupy the position shown in full lines in Fig. 23 and thus will not be at such an elevation as to engage the push finger 356 during normal weaving cycles of the loom. How-

ever, when a transfer is to be made and cell #1 is moved vertically to transfer position, the plate 248 will be moved into the position illustrated in broken lines in Fig. 23. Thus as the lay moves forward toward front center, the plate 248 will be brought into engagement with the inner end of the push finger 356. It will be recalled that cell #1 reaches the steadier 325 20° ahead of front center. At this same time the plate 248 may engage the finger 356 and continued forward movement of the lay will swing the lock knife 244 backward and out of the path of the lifter rod 256. Such action disengages the saddle 226 from the lift rod 256 and thereafter cell #1 is free to drop towards cell #2, once it is released from the steadier 325. Thus, for substantially the entire 40° period during which transfer is effected, cell #1 is supported by the steadier 325. The position of parts shown in Fig. 19 is such that the lay is about 20° ahead of front center. Thus, cell #1 has just engaged the steadier 325 which will continue to rock about pivot 330 while the lay advances to front center and recedes to a position slightly behind that of Fig. 19 whereupon cell #1 is withdrawn from the steadier 325.

It is essential in high speed operation that cell #1 return to its locked position in the minimum period of time after its release from steadier 325. While gravity will tend to effect such return, it has been found advisable to provide a spring to supplement the action of gravity. Thus in Fig. 12 a vertically disposed rod 358 is secured to the saddle 226 and extends through an opening in the bracket 260. At its lower end the rod 358 is provided with a collar 360. An expansive spring 362 is positioned between the collar 360 and the bracket 260 and the expansive force of the spring 362 tends to pull the assembly, including cell #1, rapidly downwardly immediately upon the release of cell #1 from the steadier 325. It will be appreciated that, dependent upon the particular pattern and chain design employed, it may be necessary for cell #1 to return from its elevated transfer position directly to race plate level for the next pick. In other instances, cell #2 may remain at race plate level for the next pick. Thus cell #1 may have to move with unusually great rapidity under the former set of conditions. In the present construction, if cell #1 is to return to race plate level, the remaining cells will start downwardly before cell #1 leaves the box steadier shown in Fig. 19 and after it leaves the steadier it must catch up as well as close the normal single cell-depth interval. The spring 362 just described not only permits the remaining cells to move away from cell #1 while it is still held on the steadier but it is also subjected to increased tension under these conditions and thus accelerates cell #1 in its return to race plate level. The locking mechanism for securing #1 cell in fixed relationship with the remaining cells for normal weaving operation has been described hereinabove, and in Fig. 21 such mechanism is shown in locked position.

If, as explained above, a different pattern requires the use of three cells of shuttle box 38, transfer may occur with cell #2 at race plate level under the same conditions that transfer may occur when only two cells are used. However, there may be instances where cell #3 is to rise to race plate level for the next pick after transfer. In such instances the unit comprising cells #2, #3 and #4 will start to rise before transfer is complete and the space between cell #1 and cell #3 would close before the exhausted quill is ejected. Thus, the chain must be so arranged as to prevent transfer in any cycle where cell #3 is needed for the next pick. The revoker mechanism, to be explained hereinbelow, may be availed of for this purpose. Also, as explained above, the magazine 40 may be positioned at a different level and the safety stop 201 may be differently positioned, as for instance when it is desired to use four or more cells or when for other reasons it is desired to effect transfer with a different cell at race plate level, but it will be apparent that the lifting,

steading and return mechanism for cell #1 can be adapted without change in principle or operation to such conditions.

The detector mechanism which operates to initiate transfer when such is appropriate will now be described with particular reference to the cooperation between such detector mechanism and the novel split box arrangement constituting a feature of the present invention. The detector mechanism may take any suitable form but in the present embodiment of the invention there is illustrated a detector mechanism commonly employed in the Crompton & Knowles loom which has been chosen for illustration herein.

Referring first to Fig. 17, the detector mechanism includes a feeler 364 which is pivoted at 366 to a feeler slide 368 which is movable fore and aft upon a feeler bed indicated generally at 370 in Fig. 20. The feeler bed 370 is secured to a vertical slide 372 (see Fig. 16) which in turn is vertically slidable in a vertically disposed bed 374 carried by a part of the detector stand 376.

Referring now to Fig. 14, the detector stand 376 depends from a horizontally disposed shaft 378 carried by the lower portion of the magazine 40. As described above, the magazine 40 rests upon a spacer 52 which in turn is supported from the breast beam of the loom. The mechanism just described serves to mount the detector mechanism for generally vertical movement to correspond with vertical movement of the shuttle box 38 and also provides for horizontal movement of the feeler 364 when the lay moves forward toward front center position. The detector mechanism also includes (see Fig. 17) a feeler revoker finger 380 which prevents contact of the feeler 364 with a bobbin in the event a shuttle is improperly positioned in the cell. As will be well understood, the feeler 364 moves vertically with the change box mechanism so as to remain constantly positioned opposite the particular cell in which detection is to occur.

In the arrangement shown in the drawings, detection occurs immediately after a shuttle enters cell #1 and during the same forward movement of the lay. In the event the feeler 364 engages a filled bobbin, the horizontal detector slide will be moved backwardly away from the position shown in Fig. 17 but in the event it engages an empty quill such as that shown at 444 in Fig. 17, there will be insufficient friction between the free end of the feeler 364 and the smooth surface of the quill to bring about such backward movement. As is usual in the type of detector mechanism herein disclosed, the feeler 364 is provided at its free end with a coil spring 382 which will bite into the turns of yarn upon a filled bobbin whereupon the feeler will be unable to swing about its pivot 366, thus establishing a relatively rigid connection through which the feeler slide 368 is caused to move backwardly as the lay continues forwardly to front center. The coil spring will slip over the smooth surface of an empty quill resulting in a clockwise rotation of the feeler finger 364 around its pivot 366 whereupon no backward motion will be transmitted to the slide 368. In accordance with the present invention, the mechanism is so arranged that transfer will occur on the next pick as a result of the failure of the slide 368 to move backwardly provided that the shuttle carrying the exhausted quill is to remain in cell #1 during the next pick. It should be noted that Figs. 17 and 20 show the parts one pick ahead of the position shown in Figs. 12, 16 and 19.

Each time a sufficiently filled bobbin is detected, the slide 368 will move backwardly as viewed in Fig. 17 to swing an inter-indicator finger 384 about a pivot 386. As shown in Fig. 14, the inter-indicator finger 384 is an elongated flat blade so arranged that it may be operated by the detector slide irrespective of the various vertical positions which such slide assumes in following the motions of the change box mechanism. An indicator finger 388 is fixed upon an indicator shaft 390 which is urged to rotate by a torsion spring 392 in such direction as con-

stantly to press the indicator finger 388 against the inter-indicator finger 384. The indicator shaft 390 has fixed toward its left-hand end, as viewed in Fig. 14, a plunger push arm 394 to which is pivoted a plunger 396.

Referring now to Fig. 16, the plunger 396 extends into an opening 398 in the detector stand 376. The opening 398 intersects a vertically disposed slot 400 in the detector stand 376 which receives the free end of a detector lever 402 (see Fig. 14). The plunger is of such length that it may be projected through the opening 398 and beyond the slot 400 and the torsion spring 392 on the detector shaft 390 tends constantly to urge the plunger to the latter position. However, upon each backward motion of the feeler slide incident to detection of a full bobbin, the detector shaft 390 will be rotated to withdraw the plunger 396 into the position shown in Fig. 16 in which the inner end 397 thereof lies forward of the slot 400. When a shuttle having an empty bobbin therein arrives in proper position in #1 cell, the feeler slide will not be moved backwardly as explained hereinabove, in which event the plunger 396 will remain in such position that it intersects the slot 400. When the plunger 396 remains in this position a transfer cycle will occur in the next pick unless the revoker mechanism, to be described hereinbelow, intervenes.

Referring now to Fig. 14, a detector lever 402 is freely pivoted at 404 at the lower end of indicator connector 405 and intermediate its length receives a stud 408 on the head 410 of the detector rod 196. As described above in connection with Fig. 10, the detector rod 196 makes one complete reciprocation for each pick. In the position of the parts shown in Fig. 14, which corresponds with the position of the cam illustrated in Fig. 10, the detector rod 196 is moving downwardly. If the plunger 396 is withdrawn from slot 400 as shown in Fig. 16, the detector lever 402 is free to swing down in the slot 400. This is the condition normally assumed when no transfer is to occur. However, when transfer is to occur, the plunger 396 will be projected beyond the slot 400 at the time that the detector lever 402 is in its uppermost position. Thus upon downward movement of the detector rod 196, the lever 402 will strike the plunger 396 which thereupon acts as a fulcrum around which the lever 402 will swing downwardly to pull an indicator-connector 405 downwardly. At its upper end the indicator-connector 405 is pivoted at 412 to an indicator-plunger 414 which is fixed to a connector shaft 416 on magazine 48. Downward movement of the indicator-connector 405 imparts counter-clockwise rotation to the connector shaft 416. Such operation initiates functioning of the magazine and the transfer mechanism.

Since many details of the magazine are of no consequence insofar as the present invention is concerned, reference is made to Patent No. 2,360,529 granted October 17, 1944 to R. G. Turner, for a detailed disclosure of a suitable type of magazine which may be used in connection with the present invention. A magazine such as that shown in said Turner patent has been illustrated in the present drawings. Also, the mechanism shown in particular in Fig. 15 forms a part of the structure shown in Patent 2,399,457 granted April 30, 1946 to E. C. Alix et al. As clearly disclosed in said Turner and Alix et al. patents, rotation of the indicator shaft 416 will cause downward motion of one of four slides which serve to open the particular cradle from which a new bobbin must be supplied to replace the exhausted bobbin. The selection of the particular color or type of filler required is carried out by the mechanism shown in Fig. 15 herein and shown in more detail in said Alix et al. patent, under the control of color selecting mechanism provided in accordance with the present invention and to be described in detail hereinbelow.

Upon the opening of the proper cradle the selected bobbin will drop into transfer position and, as an incident to the opening of such cradle, a preventor shaft 418 will

be rotated clockwise, as viewed in Fig. 14. The preventor shaft 418 has fixed thereto a lever 420 which is pivotally connected at its outer end to a head 422 on a connector 424 for operating the latch mechanism which controls the bobbin changing or transfer hammer. The latter mechanism is shown in detail in said Turner patent and is also illustrated in Fig. 16 herein. The connector 424 is pivotally connected at its lower end to a transfer latch 425 fastened at 426 to a latch holder 428. The latch holder 428 is pivoted at 429 to and depends from an arm 430 of the transfer hammer. The transfer hammer includes a head 432 on the free end of an arm 434 and is pivoted on the hanger shaft 378. When the connector 424 is moved downwardly the latch 425 will be raised into the position illustrated in Fig. 16 wherein the notched end 427 thereof is positioned in the path followed by a dog 438 secured to cell #1 of the shuttle box 38 when cell #1 has been separated from the remainder of the cells in said box preparatory to transfer, all as illustrated in Fig. 16. When the parts are in such position, forward motion of the lay will be transferred through the dog 438 and latch 425 to the transfer hammer 432, 434, which will rock clockwise to engage the filled bobbin in transfer position and carry the same downwardly into the shuttle positioned in cell #1.

The position illustrated in Fig. 16 is that assumed after the hammer has been moved a distance sufficient to carry the new bobbin from transfer position to a point where it is entering the shuttle and displacing the empty bobbin therefrom. In said Fig. 16, the head 432 of the transfer hammer has not completed its stroke and it will be observed that a filled bobbin 440 is just entering shuttle 442 in cell #1 to displace an exhausted bobbin 444. As will be explained hereinbelow, the movement of cell #1 into the transfer position illustrated in Fig. 16 has already been effected as an incident to operation of the magazine in response to an indication by the detector mechanism. As the transfer hammer continues its stroke the exhausted bobbin 444 emerges from the shuttle 442 and enters the space between cell #1 and cell #2.

As shown in Fig. 16, a chute 446 is freely pivoted or hinged at 448 along the rear lower edge of cell #1. The chute 446 is shown in front elevation in Fig. 12 and it will be observed that it is so positioned as to lie in the path of the exhausted bobbin 444 which is being ejected in the point of the cycle illustrated in said Figs. 12 and 16. In Fig. 21, the chute 446 is shown in collapsed position in which it lies flatwise between cells #1 and #2. The hinge 448 on chute 446 is a freely working hinge preferably of the type normally referred to as a piano hinge inasmuch as with such a hinge gravity alone may be depended upon for causing a chute to assume the open position illustrated in Figs. 12 and 16 whenever cell #1 is elevated away from cell #2. Obviously the movement of the chute 446 may be effected in any manner found desirable although the gravity operation herein illustrated has been found to be satisfactory in the particular installation chosen for the present disclosure. As will be apparent from an inspection of Fig. 16, the chute 446 assumes a downwardly inclined position beneath cell #1 wherein it will serve to deflect a bobbin ejected from a shuttle in cell #1 in a generally horizontal direction, whereupon the exhausted bobbin may drop free of the loom. It will be apparent also that dependent upon the particular shuttle box or the particular loom in which a particular shuttle box may be installed, that the chute 446 may be arranged to discharge exhausted bobbins in any direction which may be desired. Thus, for example, the chute may be arranged to discharge the bobbins toward the rear of the loom if that may be convenient or necessary in a particular installation.

The relationship of parts shown in Fig. 16 clearly illustrates the operation of the present invention in effecting transfer at a time when a shuttle 450 is positioned in cell #2 of the shuttle box 38. As explained hereinabove,

in looms heretofore available, automatic weft replenishment with color selection or filling mixing have been limited to the use of the magazine end, a shuttle box having only two cells and transfer could only occur when the lower cell was empty to permit ejection of the exhausted bobbins. The increased flexibility offered by the present invention is apparent when only two cells are used but it also should be emphasized that the present invention makes it possible to effect automatic weft replenishment in a loom of the general type herein illustrated wherein three, four or more cells are provided in the shuttle box at the magazine end of the loom. Furthermore, if it may be desired to provide magazines at both ends of the loom, weft replenishment may occur at either end, in a loom having two or more cells at each end of the loom, thus giving extreme flexibility in patterns.

The present invention makes it possible to weave automatically an enormous number of patterns which heretofore have been obtainable only in non-automatic box looms. For example, the two shuttle, 2 x 2 arrangement shown in the Figures of the drawing so far described, provides fully automatic pick and pick operation. Also, it is possible, by the use of four cell magazines and four cell splitting shuttle boxes at both ends of the loom to provide automatic weft replenishment for seven shuttles, each having a different color, and to weave patterns having seven consecutive single picks, each from a different shuttle, in any desired order or sequence. Obviously the same result could be obtained with a magazine at one end only of the loom, provided such magazine is equipped with an appropriate number of cells. Also, with the four cell magazine and four cell splitting box, illustrated herein, at only one end of the loom, it is possible to use seven shuttles in the weaving of patterns employing as many as four different colors, twists, or the like, for better distribution or mixing where that may be desirable.

As stated above, the splitting of cell #1 away from cell #2 for the purposes of transfer is initiated only when a transfer is to occur. A preferred arrangement for this purpose is illustrated herein where operation of the magazine in response to the indicator mechanism is availed of to initiate the independent movement of cell #1. Obviously other alternatives could be adopted for this purpose if so desired. According to the preferred disclosure the mechanism for initiating such independent movement of cell #1 is actuated by a lever 420 (see Fig. 14) fixed to the preventor shaft 418 of the magazine 40. It will be recalled that the preventor shaft 418 rocks in a clockwise direction as viewed in Fig. 14, as an incident to operation of the magazine 40. Thus for the purposes of the present invention, a downwardly extending link 452 is pivotally attached at 454 to the lever 420. The link 452 extends downwardly as shown in Fig. 16 and is pivotally connected at 456 to a lever 458 which is pivoted intermediate its length at 460 on the detector stand 376. At its opposite end the lever 458 is pivotally connected to a downwardly extending link 462 pivoted at its lower end at 464 to a lever 466. The lever 466 rocks about a pivot 468 mounted on the rocker arm 470 and at its free end is pivoted at 472 to the lower end of the link 288. The linkage just described is effective upon initiation of operation of the magazine 40 to pull downwardly on the link 288 which, as described above in connection with Fig. 24, throws the lock knife 244 into the path of the lifter rod 264 (Fig. 25) to elevate cell #1 relative to the remaining cells in the shuttle box 38.

As mentioned above, the arrangement illustrated provides for feeling of the bobbins in cell #1 and thus the feeler mechanism is arranged to follow cell #1 in its vertical motions while it is locked to the remaining cells in shuttle box 38. To this end, as shown in Fig. 16, a link 474 is connected at the lower end of the vertical feeler slide 372 and extends downwardly where it is attached to the box lifter tube 36. In this manner the feeler slide 372 moves vertically along with the shuttle box 38. How-

ever, when a transfer is to be effected, cell #1 moves vertically independently of the remaining cells and the feeler mechanism does not follow cell #1 in such independent movement. As clearly seen in Fig. 16, the feeler thus remains at a level intermediate cell #1 and cell #2. When the lay goes forward with cell #1 in its independently elevated position, it is necessary to withdraw the feeler into the position illustrated in Fig. 16. Otherwise it would project into the space directly beneath cell #1 where it would interfere with the discharge of the exhausted bobbin therefrom. A convenient manner of withdrawing the feeler is illustrated herein. In Fig. 16, an extension arm 476 is secured to the arm 430 of the transfer hammer. The extension arm 476 engages a striker plate 478 fastened to the feeler slide 368 (see Fig. 17), when the hammer swings downwardly for the purpose of changing bobbins. Engagement between the extension arm 476 and the striker plate 478 moves the feeler slide rearwardly from a position such as that shown in Fig. 17 to a position wherein a catch plate 480 on the feeler slide passes over a rounded nose 482 formed on a holding pawl 484. The holding pawl 484 is pivoted to swing in a horizontal plane and is urged by a coil spring 486 against a stop 488, as shown in Fig. 17. When the catch plate 480 moves rearwardly and passes over the rounded nose 482, the pawl 484 will swing against the tension of spring 486 and thereafter will snap over the catch plate 480 to hold the feeler slide 368 in retracted position.

It is desired to retain the feeler retracted position not only during the transfer operation at the end of which the hammer returns to its original position but also during the ensuing operation of the loom during which cell #1 must return to its locked position illustrated in Fig. 21. To this end the holding pawl 484 is pivoted on bracket 490 secured to the hanger forming a part of the detector stand 376. It will be recalled that the detector stand 376 is stationary and thus the holding pawl 484 occupies a position in a fixed horizontal plane. This plane is such that the holding pawl 484 will engage the catch plate 480 only when the feeler slide is moved backwardly by the hammer arm extension 476. This operation occurs only when cell #2 is at race plate level and cell #1 is elevated to transfer position. When it occurs the feeler slide is moved into the position indicated in broken lines in Fig. 20. After the transfer operation has been effected and cell #1 starts back down towards cell #2, the feeler slide will remain latched in the retracted position.

As illustrated in full lines in Fig. 20, the feeler 368 has just detected an empty bobbin 444 in cell #1 and the feeler slide 368 will therefore not be moved backwardly and the transfer cycle will be initiated. The lay, after completing its forward motion to front center position, will then move back and shuttle box 38 will rise to position cell #2 at race plate level. The feeler mechanism will also rise to the level indicated in broken lines in Fig. 20. It is at such level that the extension 476 on the transfer hammer will move the feeler slide backward to engage the catch plate 480 with the holding pawl 484. As shown in Fig. 20, the catch plate 480 and holding pawl 484 are so proportioned and positioned that the lower edge of the catch plate 480 will engage the pawl 484. If the next pick requires the return of cell #1 to race plate level, as would be the case in two-shuttle pick and pick weaving, it is essential that the feeler slide be retained in its retracted position until cell #1 has been locked to cell #2 and has been moved substantially to race plate level. Thus the catch plate 480 has a vertical dimension substantially equal to the depth of cell #1 and as the feeler mechanism moves downwardly with the shuttle box 38 and away from the position shown in broken lines in Fig. 20, the catch plate 480 will remain behind the pawl 484 to retain the feeler slide 368 in retracted position for the desired period of time. At the end of such

period, the upper edge of the catch plate 480 will fall below the pawl 484 and the feeler slide 368 will be released to move forwardly into operative position for the next pick.

At several points in the above specification, reference has been made to the fact that operation of the transfer mechanism should not occur under certain combinations of conditions. In the embodiment shown the detector mechanism operates on the shuttle in cell #1. If there is no shuttle in cell #1 the feeler slide will not move and the indicator mechanism must be rendered inoperative to avoid a false indication. Beyond this, since detection occurs on one pick and transfer occurs on the next consecutive pick, operation of the indicating mechanism should be prevented at any time wherein a shuttle has entered cell #1 but is to be picked from that cell on the next cycle. Also, the indicator mechanism should be rendered inoperative in any pick which is to be followed by the positioning at race plate level of any cell other than cell #2 in the particular embodiment so far described. For example, as stated above in connection with 3 x 3 operation, the indicating mechanism should be prevented from operation in the event cell #3 is to rise to race plate level on the next pick. These are intended only as illustrative of occasions when revocation of the transfer operation might be desirable in 2 x 2 or 3 x 3 operation. Obviously when four or more cells might be used in the shuttle box beneath a magazine there may be other occasions apparent to those skilled in the art in which initiation of the transfer cycle should be prevented. Furthermore, it will be apparent that the revoker mechanism of the present invention is not limited in its application to the particular combination shown. The ability to prevent or postpone the initiation of a transfer cycle would be of value in straight automatic and filling mixing operation of the type of loom herein illustrated as well as in comparable operation of looms of other types.

The revoker mechanism herein provided is actuated by the head motion. As a matter of convenience the box pattern chain is provided with a special set of risers and sinkers 98 and 100 which operate the vibrator 82 to move the revoker linkage 46, all as described above in connection with Figs. 4 and 5. As pointed out above, a riser 98 will serve to pull the revoker link 46 to the left, as viewed in Fig. 4, whereas a sinker 100 will position the link 46 as shown in Fig. 4. The revoker link 46 extends across the loom and downwardly into the drive end thereof as shown in Fig. 1. The link 46 may be made up of rod and cable or chain sections as is usual in loom construction and is conducted over truck rolls such as 491 and 492 in Fig. 1. From the truck roll 492 the link 46 extends forwardly as viewed in Fig. 1 and the end thereof is connected as shown in Fig. 18 to the upper end of a revoker lever 494 pivoted at 496 on a revoker bearing 498 secured to the foot of the magazine 40. At its lower end the revoker lever 494 is connected with one end of a contractile spring 500, the other end of which is secured to the spacer 52. The spring 500 thus serves to urge the revoker lever 494 to rock clockwise about its pivot 496 and to tension the link 46 all the way back to bell crank 88 (see Fig. 4). When a sinker 100 is positioned beneath the shoe 84 the spring 500 will move the revoker lever 494 (Fig. 18) into the dotted line position. When a riser 98 is positioned under the shoe 84, the linkage described above will be effective to pull the lever 494 against the tension of spring 500 and into the full line position shown in Fig. 18.

Referring now to Fig. 14, the revoker lever 494 has secured at its lower end a revoker pin 502 which extends laterally of the lever 494 into a position to engage the upper end of an indicator arm 504 secured at its lower end to the indicator shaft 390. With the parts in the position shown in full lines in Fig. 18, which corresponds with the presence of a riser 98, operation of the transfer mechanism will be prevented because the indicator

shaft 390 has thus been rocked clockwise as viewed in Fig. 18, thus to withdraw the plunger arm 394 (see Fig. 14) and the plunger 396 carried thereby from the plunger housing 376 (see Fig. 16). In this position of the parts, as explained hereinabove, the end 397 of plunger 396 is withdrawn from the slot 400 to prevent initiation of the transfer cycle. Such operation of the revoker mechanism will prevent initiation of the transfer cycle even though the detector has come into engagement with an exhausted quill or has entered an empty cell and has not moved the feeler slide rearwardly. It thus will be apparent that the revoker mechanism places an overriding control of the transfer mechanism in the box pattern chain and the latter can be so designed as to prevent operation of the transfer mechanism at any time desired.

The present invention also provides a simple and direct control which may be exerted from the box pattern chain for selecting the desired color, twist, or the like, from the magazine 40. The particular loom chosen for illustration herein is equipped with a filling mixer attachment of the type shown in U. S. Patent No. 2,399,457. Such attachment is originally designed to supply each of two shuttles alternately from two sources. According to the present invention such attachment may be so adapted that a filled bobbin may be selected from any one of the four cells in magazine 40.

Referring first to Fig. 1 and Fig. 3, the color selector link 48 is controlled by a special vibrator 58 and a special set of risers and sinkers 94 and 96 (see Fig. 5), all as described above. A riser 96 will cause the color selector link 48 to be moved to the left as viewed in Figs. 1 and 3. The color selector link 48 is conducted over the truck rolls 491 and 492 and extends forwardly as viewed in Fig. 1 and is connected to a color selector lever 510 (see Fig. 15). The position of parts shown in Fig. 15 corresponds with the presence of a sinker 94 on the box pattern chain and thus represents the extreme right hand position to which the lever may be moved. Although the apparatus shown is adapted for the selection of four different colors, the particular illustration chosen for the first example makes use of only two colors and for that reason the box pattern chain is provided with risers and sinkers and the lever 510 is moved between two positions. When three or four or more colors are used, the box pattern chain will be provided with risers of varying sizes in order that the lever 510 may be moved to a suitable number of different positions. The rocking of lever 510 shifts the connector shaft 416 which, as indicated above, is also rotatable for the purpose of initiating the transfer cycle. Horizontal movement of the connector shaft 416 into different definite positions serves to select the proper bobbin from the magazine 40. As disclosed in full detail in said Patent No. 2,399,457, the horizontal displacement of connector shaft 416 is operative through the mechanism indicated generally at 512 and 514 to impart vertical movement to any particular one of a group of vertical slides 516, each of which is connected to a particular cell within the magazine so as to release the bobbin from such cell when desired. It will be apparent, therefore, that the box pattern chain may be availed of directly to select a bobbin from the magazine 40 in accordance with any specific demand. For instance, if only two colors are being used, as in the first example chosen for illustration herein, the box pattern chain may be so laid out as to supply the proper color whenever a particular quill is exhausted. In that event, the mechanism disclosed in detail in said Patent No. 2,399,457 may be availed to mix two sources of the same color by alternating replenishment between two magazine cells assigned to such color. However, if four colors are to be used, each color will come from a particular cell in the magazine as will be clearly understood.

In Fig. 22 there is shown a suggested form of electrical means for controlling a stop motion to bring the loom

to a stop in the event cell #1 of the splitting shuttle box 38 fails to return to proper locked position after transfer. Fig. 22 is a fragmentary end elevation corresponding with Fig. 21 but showing parts at the right hand end as viewed, for example, in Fig. 25. A switch 518 is secured to the boss 222 and this switch is preferably a micro-switch having a roller actuating arm 520. An angle bracket 522 is secured to the boss 214 on cell #1 and this bracket carries a switch actuating cam having an extensive flat portion 524 and an outwardly flared portion 526. The actuating arm 520 assumes one position when cell #1 is properly locked inasmuch as the flared portion 526 permits the arm 520 to spring outwardly as illustrated in Fig. 22. The flat surface 524 engages the actuating arm 520 and holds the switch in an opposite position whenever cell #1 is moved away from cell #2. The switch 518 may be either normally open or normally closed depending upon the type of control circuit in which it is placed. Assuming that the switch is of the normally open type, it will be opened only when cell #1 is in locked position. At all other times the switch will be closed. Thus whenever a transfer is made and cell #1 splits away from the remaining cells, switch 518 will be closed and will complete a circuit between wires 528 and 530. When transfer is complete and cell #1 drops into final position wherein it may be locked by the locking pawls 228 and 230, the switch 518 will be opened, thus breaking the circuit between wires 528 and 530. A suitable stop motion, brake or the like (not shown) may be arranged to respond to the condition of the circuit including wires 528 and 530 whereby to stop the loom if cell #1 is not returned to proper position at a suitably predetermined instant in the cycle of operation, as will be well understood by those skilled in the art.

The operation of the various components of the present invention and the cooperation therebetween have been described hereinabove as the detailed description has proceeded. The overall operation of the loom embodying the present invention will be briefly described in connection with diagrammatic Figs. 27 through 33 wherein illustrative methods for weaving several selected patterns are disclosed.

In Figs. 27 and 28, the selected pattern is woven in alternating pick and pick relation with white and brown yarns carried respectively in two shuttles and in which only two cells of each shuttle box are used. These figures illustrate the operation which has been used as a primary example in the detailed description hereinabove. Thus the shuttle boxes 28 and 38 shown diagrammatically in Fig. 27 are illustrated as four-cell boxes although only cells #1 and #2 are used in each and the particular operation illustrated in Fig. 27 obviously could be carried out with two-cell shuttle boxes if so desired. However, a primary purpose of the present portion of the specification is to illustrate the great flexibility imparted to a loom by the embodiment therein of the present invention and in any commercial installation wherein such flexibility may be desirable, it is most likely that the embodiment would be made in a loom having at least four cells in each of its shuttle boxes.

It will be observed that the box pattern chain diagrammatically illustrated in Fig. 28 is the same as the one shown in Fig. 5 except that two complete cycles of eight picks are shown in the latter figure. Thus in Fig. 5, bars No. 9 through No. 16 correspond respectively with bars No. 1 through No. 8. Similarly in Fig. 28 bar No. 9 corresponds with bar No. 1. The various positions of the shuttle boxes and shuttles illustrated in Fig. 27 are numbered to correspond with the numbering of the bars illustrated in Fig. 28 and Fig. 5. The remaining Figs. 29 through 33 follow the same plan. The shuttle diagrams (Figs. 27, 29, 31 and 32) may be assumed to represent the instant in each pick cycle wherein a shuttle starts to move in the direction indicated by the arrow extending over the race plate. It will be understood

that the box pattern chain bars which correspond to the shuttle diagrams in each instance will have been moved into operative relation with the vibrator shoes well ahead of the time indicated in the correspondingly numbered 5 shuttle diagram. Thus shifting of the shuttle boxes, detection, indication and transfer, if needed, as called for by a particular bar will be completed during the latter part of the preceding pick and in the early part of the correspondingly numbered pick before the shuttle 10 starts its traverse.

It is customary to regard the pick cycle as commencing when the lay is in front center position. In a typical cycle the lay is at front center at 0°, the shuttle starts to move at about 90° and homes at 180° to 210°, the next chain bar engages the vibrator shoes at about 240° and the box shifting, detecting and transfer operations for the next pick thus commence at about 240° and must be completed before the shuttle starts to move in said next pick.

20 In the first position illustrated in Fig. 27, a white shuttle is positioned in cell #1 and a brown shuttle is positioned in cell #2 of shuttle box 28. There are no shuttles in box 38. Cells #1 of both boxes are at race plate level having been moved to such level by bar No. 1. In this first pick the white shuttle will move from cell #1 of box 28 to cell #1 of box 38 and bar No. 2 of the box pattern chain will move into operative position and both boxes will rise to bring cells #2 to race plate level in preparation for the second pick. On the second pick the brown shuttle will move from cell #2 of box 28 to cell #2 of box 38. Both boxes will then be lowered to bring cells #1 to race plate level and on the third pick the white shuttle will be moved from cell #1 of box 38 to cell #1 of box 28. From a consideration of the three picks just described, it will be apparent that the white shuttle which enters cell #1 of box 38 on the first pick will remain in that cell during the second pick in which cell #2 is brought to race plate level and thereafter will remain in cell #1 until the box 38 is lowered and the sliding pick motion is operated in the course of the third pick. As described above, this is the condition under which transfer may occur when the loom is equipped in accordance with the present invention. Thus as the lay moves forward towards the end of the first pick the detector mechanism will operate upon the white shuttle in cell #1 of box 38. As shown in Fig. 28, a sinker 100 is positioned upon bar No. 2 and the revoker mechanism described above is rendered inoperative so that a transfer cycle will be initiated in the event the bobbin in the white shuttle is exhausted. Assuming that to be the case, transfer will occur as described above during the latter part of the second pick and the early part of the third pick and transfer will be completed in time for the replenished white shuttle to be picked from cell #1 of the box 38 in the course of the third pick. The improvement brought about by the present invention over the types of automatic operation heretofore available by conversion of such "convertible" looms will become apparent upon a consideration of the operation just described. In the second pick the brown shuttle is moved into cell #2 of box 38 and if this loom were equipped for straight automatic operation, as heretofore available, transfer could not be effected because it is necessary to have cell #2 empty in order for the exhausted quill to be discharged therethrough. The present invention, which provides for independent movement of cell #1 away from cell #2 and the interpositioning of the chute 446 therebetween, makes it possible to transfer even though cell #2 be occupied by a shuttle.

70 From a consideration of bars No. 1, No. 2 and No. 3 in Fig. 28, it will be observed that risers 98 are provided on bars No. 1 and No. 3 and a sinker 100 is provided, as stated above, upon bar No. 2. Thus the revoker mechanism is effective to prevent transfer when either bar No. 1 or bar No. 3 is positioned beneath the shoes of the vibrators in the head motion. The provision of the

revoker mechanism controlled by the head motion, in combination with the splitting shuttle box 38 and the operation of the detector mechanism during each pick makes it possible to provide automatic weft replenishment in connection with alternating pick and pick weaving with two colors and two shuttles while achieving full production at normal loom speeds.

It will be observed that proper color selection is controlled by the line of risers and sinkers 96 and 94 carried by the bars of the box pattern chain. Thus sinkers 94 are provided on bars No. 1, No. 2 and No. 3 and as described above a bobbin will be selected from one of the cells of the magazine 40 if transfer is to occur as just described. In the present instance, therefore, white bobbins are positioned in that cell of magazine 40 which is selected when a sinker is positioned beneath the vibrator 58 (see Fig. 3).

During the fourth, fifth and sixth picks the brown and white shuttles follow one another to perform pick and pick weaving and in the sixth pick the brown shuttle is moved from cell #2 of box 28 to cell #1 of box 38. In preparation for the seventh pick box 38 rises to bring cell #2 to race plate level and the white shuttle is picked from cell #2. On the eighth pick the brown shuttle will be picked from cell #1. Under these conditions detection of the brown shuttle may occur towards the end of the sixth pick and transfer may occur during the seventh and eighth picks if necessary. Thus a sinker 100 is positioned on bar No. 7. Assuming a transfer is to be made, cell #1 of box 38 will split away from cell #2 while cell #2 is at race plate level. This brings cell #1 up to transfer position and transfer may occur in spite of the fact that cell #2 is occupied by the white shuttle. During the course of the sixth pick in which detection occurs, the brown shuttle will be picked from cell #2 of box 28 and in the seventh pick the white shuttle is picked from cell #2 of box 38. For the eighth pick the box 38 must be lowered in order that the replenished brown shuttle may be picked from cell #1. As described above, the split box mechanism is so arranged that cell #1 rests upon the steadier 325 and thus is held in proper relationship with magazine 40 for completion of transfer even though cell #2 begins to drop below race plate level. In the course of such operation the spring 362 (Fig. 12) is compressed and as soon as the lay moves backwardly about 20° from front center, cell #1 is withdrawn from the steadier 325 and will drop through the combined action of gravity and the spring 362 to catch up with cell #2 and be locked in proper weaving position by the time cell #1 reaches race plate level. Immediately thereupon the replenished brown shuttle may be picked from cell #1.

The box pattern chain is provided with risers 96 on bars No. 7 and No. 8. The risers 96 operate the color selector mechanism hereinabove described so as to select a bobbin from the particular cell of magazine 40 which contains brown bobbins. Obviously in an operation such as that just described, the white filling or the brown filling or both may be mixed from two different cells of magazine 40, if so desired, by making use of the A. & W. filling feeding attachment as shown herein and as described in detail in U. S. Patent No. 2,399,457.

In Figs. 29 and 30 there is illustrated a weaving operation in which four shuttles each having a different color are used in a 4 x 4 arrangement to weave a pattern in alternating pick and pick sequence. That is to say, the four colors will appear in 1-2-3-4, 1-2-3-4, etc. sequence. The principles of operation under these conditions are the same as those described in detail above except that all four cells of the shuttle boxes 28 and 38 are used and the box pattern chain will thus have a full complement of risers and sinkers in those chain spaces assigned to box lift motion. The magazine 40 will be elevated to accommodate the additional lift of the shuttle box 38. Also, the color selector and filling feeder will be operated so as to supply a different color

from each of the four cells of the magazine 40. To this end the box pattern chain is provided with appropriately disposed, graduated risers 96A, 96B, 96C and 96D. Obviously the smallest riser 96A could be a sinker. The four different degrees of movement thus imparted to the color selector linkage 48 (see Fig. 1) will operate the mechanism illustrated in Fig. 15 to select a bobbin from the desired cell of magazine 40.

From a consideration of the sequence of shuttle motion illustrated in Fig. 29, it will be apparent that detection of the blue shuttle may be made towards the end of the first pick and transfer may be effected during the latter part of the second and early part of the third picks. Similarly, detection of the red shuttle may be made on the sixth pick, detection of the green shuttle may be made on the eleventh pick and detection of the brown shuttle may be made on the seventeenth pick. Transfer of these respective shuttles may be effected during appropriate parts of succeeding picks. Thus in a 24-pick cycle, it is possible in accordance with the present invention to provide for detection and transfer of all four shuttles. It will be noted that sinkers 100 are positioned upon bars No. 2, No. 7, No. 12 and No. 17 to disable the revoker so that transfer may be effected if the detector operates the indicator mechanism. Risers 98 on all remaining bars operate the revoker and thus prevent false transfer.

As explained hereinabove, transfer should occur with cell #3 of box 38 at race plate level when three or more cells are used. Thus, to condition the loom for the operation illustrated in Figs. 29 and 30, a different spacer block 52 must be positioned in the loom (see Fig. 1) to raise the magazine 40 to proper level for cooperation with cell #1 when that cell is split away from the remaining cells and cell #3 is at race plate level. Alternatively, of course, an additional spacer block (not shown) may be added between the block 52 and the foot of the magazine 40 to accomplish this same result if that be deemed desirable. Also, it should be pointed out that the mechanism shown in Fig. 15, must be adjusted to select a particular color from a particular cell of magazine 40 in response to the graduated motion of the color selector linkage.

In Figs. 31, 32 and 33 there is shown an operation in which seven shuttles, each with a different color, may be automatically replenished in a weaving operation wherein the sequence is 1-2-3-4-5-6-7, 1-2-3-4-5-6-7, etc. Here all four cells of the shuttle boxes 28 and 38 are used. Obviously the magazine 40 illustrated herein cannot serve to replenish seven different colors and thus a different magazine having an appropriate number of cells must be provided if transfer is to occur only at the drive end of the loom. It will be apparent, however, that four-cell magazines might be placed at both ends of the loom and a split shuttle box like the box 38 illustrated herein might be positioned at the head end as well as at the drive end of the loom. In such instance transfer could occur at both ends of the loom if so desired.

The operation illustrated in Figs. 31, 32 and 33 is based upon the assumption that a magazine having at least seven cells is positioned at the drive end of the loom. The colors are identified by the capital letters A, B, C, D, E, F and G and the first fourteen picks are illustrated in Fig. 31 in the same manner as heretofore used in Figs. 27 and 29. The remaining picks are illustrated in a somewhat simpler form. A consideration of the shuttle motions illustrated in Figs. 31 and 32 will reveal that transfer of color G may be initiated in the seventh pick and may occur during the eighth and ninth picks inasmuch as the shuttle G entered cell #1 of box 38 during the seventh pick and cell #3 of box 38 will rise to race plate level for the eighth pick and will remain at race plate level during the early part 75 of the ninth pick. Under these conditions shuttle G

may be detected in the seventh pick and as shown in Fig. 33, a sinker 100 will be positioned on bar No. 8 to disable the revoker mechanism thereby to permit transfer in the event shuttle G is exhausted. Assuming exhaustion of shuttle G, transfer will occur during the latter part of the eighth and early part of the ninth pick and the color G will be selected by the positioning on bars No. 8 and No. 9 of the box pattern chain of a suitably graduated riser 96G. Similarly, detection of shuttle A may occur in the fifteenth pick and transfer may be effected if necessary during the next two picks, the proper color being selected as a result of the positioning on bars No. 16 and No. 17 of a suitably graduated riser 96A. As clearly shown in Fig. 33, the remaining colors B, C, D, E and F may be transferred on the twenty-fourth, thirty-second, fortieth, forty-eighth and fifty-sixth picks respectively. Risers 98 are positioned upon the box pattern chain to prevent initiation of transfer during all other picks. Thus in a 56-pick cycle, it is possible in accordance with the present invention to provide for automatic weft replenishment when weaving seven colors in alternating pick and pick sequence.

The various types of pick and pick weaving which have been chosen for illustration herein were chosen as extreme examples of the type of flexibility which may be imparted to a loom by the present invention. Obviously an almost infinite number of patterns involving, in some instances, less complication insofar as automatic weft replenishment is concerned, may be woven with a loom equipped as taught herein. For example, many fancy patterns which may involve only an occasional single pick may be woven automatically in accordance with the present invention without loss in production or material.

A particular advantage of the present invention is that after a loom has been modified as taught herein there will be little occasion for major "conversions" thereafter. In the past it has been necessary to replace shuttle boxes and apply or remove various attachments in order to convert a loom to box operation or to straight automatic operation or to filling mixing operation as production schedules vary. In contrast with this, the present invention makes it possible to weave a vast variety of patterns, including those heretofore known as "box" and "automatic" patterns without replacing shuttle boxes and without adding or removing the magazine, filling mixing attachment, etc. In some instances, as pointed out above, it may be necessary to change the elevation of the magazine 40. Beyond this, however, the user need only to make the usual changes in pattern chains and harness arrangement.

I claim:

1. In an automatic weft-replenishing loom operating with two or more shuttles operative in any sequence including sequences in which each shuttle is active for but one pick at a time, a shifting shuttle box at each end of the loom, a magazine for reserve weft-carriers at at least one end of the loom, the shifting shuttle box at the end or ends of the loom at which a magazine is positioned having at least one cell shiftable to and from race plate level by the head motion of the loom and a cell positioned immediately above the uppermost of said first-named cells, said last-named cell being movable to and from race plate level by said head motion and as a unit with said first-named cells thus constituting an active cell in normal weaving operations, and means operative only as an incident to initiation of a transfer cycle for moving said last-named cell vertically relative to said first-named cells into a transfer position wherein a weft-carrier within said last-named cell may be replaced by a reserve weft-carrier from said magazine, said last-named cell when in said transfer position being spaced from the uppermost of said first-named cells a distance sufficient to permit discharge of an exhausted weft-carrier through the bottom thereof irrespective of whether there may be a shuttle in the next cell therebeneath.

2. In an automatic weft-replenishing loom operating with two or more shuttles operative in any sequence including sequences in which each shuttle is active for but one pick at a time, a shifting shuttle box at each end of the loom, a weft-detecting mechanism, a magazine for reserve weft-carriers at at least one end of the loom, the shifting shuttle box at the end or ends of the loom at which a magazine is positioned having at least one cell shiftable to and from race plate level by the head motion of the loom and a cell positioned immediately above the uppermost of said first-named cells, said last-named cell being movable to and from race plate level by said head motion and as a unit with said first-named cells thus constituting an active cell in normal weaving operations, and means operative only as an incident to initiation of a transfer cycle for moving said last-named cell vertically relative to said first-named cells into a transfer position wherein a weft-carrier within said last-named cell may be replaced by a reserve weft-carrier from said magazine, said last-named cell when in said transfer position being spaced from the uppermost of said first-named cells a distance sufficient to permit discharge of an exhausted weft-carrier through the bottom thereof and through the space thus provided irrespective of whether there may be a shuttle in the next cell therebeneath, said means for moving said last-named cell to transfer position being responsive to the weft-detecting mechanism of said loom upon detection by said detecting mechanism of a substantially exhausted weft-carrier in said last-named cell.

3. In an automatic weft-replenishing loom, a vertically shifting shuttle box at each end of the loom, a magazine for reserve weft-carriers at at least one end of the loom, the shifting shuttle box at the end or ends of the loom at which a magazine is positioned having a plurality of cells, a head motion including at least one pattern chain, means operated by a pattern chain for shifting said shuttle box to bring any one of said cells to race plate level, a weft-detecting mechanism including a feeler engageable with a weft-carrier in a cell in one of said shuttle boxes in any beat of the loom, means actuated by said feeler and adapted to initiate a transfer cycle in the next beat of the loom after said feeler engages a substantially exhausted weft-carrier, and means operated by a pattern chain to prevent initiation of a transfer cycle in any selected beat of the loom.

4. In an automatic weft-replenishing loom, a vertically shifting shuttle box at each end of the loom, a magazine for reserve weft-carriers at at least one end of the loom, the shifting shuttle box at the end or ends of the loom at which a magazine is positioned having a plurality of cells, a head motion including at least one pattern chain, means operated by a pattern chain for shifting said shuttle box to bring any one of said cells to race plate level, a weft-detecting mechanism including a feeler shiftable with said shuttle box and constantly maintained in a position to enter a predetermined cell of said shuttle box and to engage any weft-carrier which may be positioned in said cell during the course of each beat of the loom, means actuated by said feeler and adapted to initiate a transfer cycle in the next beat of the loom after said feeler engages a substantially exhausted weft-carrier or fails to engage a weft-carrier, and means operated by a pattern chain to prevent initiation of a transfer cycle in any selected beat of the loom.

5. In an automatic weft-replenishing loom, a vertically shifting shuttle box at each end of the loom, a magazine for reserve weft-carriers at at least one end of the loom, the shifting shuttle box at the end or ends of the loom at which a magazine is positioned having a plurality of cells, a head motion including at least one pattern chain, means operated by a pattern chain for shifting said shuttle box to bring any one of said cells to race plate level, a weft-detecting mechanism including a feeler shiftable with said shuttle box and constantly maintained in a position to enter a predetermined cell of said shuttle box and to

engage any weft-carrier which may be positioned in said cell during the course of each beat of the loom, indicator mechanism responsive to said weft-detecting mechanism and adapted to initiate a transfer cycle in the next beat of the loom after said feeler engages a substantially exhausted weft-carrier or fails to engage a weft-carrier, and means operated by a pattern chain to prevent said indicator mechanism from initiating a transfer cycle in any selected beat of the loom.

6. In an automatic weft-replenishing loom, a vertically shifting shuttle box at each end of the loom, a magazine for reserve weft-carriers at at least one end of the loom, the shifting shuttle box at the end or ends of the loom at which a magazine is positioned having a plurality of cells, a head motion including at least one pattern chain, means operated by a pattern chain for shifting said shuttle box to bring any one of said cells to race plate level, a weft-detecting mechanism including a feeler shiftable with said shuttle box and constantly maintained in a position to enter a predetermined cell of said shuttle box and to engage any weft-carrier which may be positioned in said cell during the course of each beat of the loom, transfer mechanism for replacing an exhausted weft-carrier in said cell with a reserve weft-carrier from said magazine, driving means adapted to operate said transfer mechanism on each beat of the loom, indicator means responsive to said weft-detecting mechanism and adapted to initiate operation of said transfer means by said driving means in the next beat of the loom after said feeler engages a substantially exhausted weft-carrier or fails to engage a weft-carrier, and means operated by a pattern chain to prevent said indicator mechanism from initiating transfer operation in any selected beat of the loom.

7. In an automatic weft-replenishing loom, a vertically shifting shuttle box at each end of the loom, a magazine for reserve weft-carriers at at least one end of the loom, the shifting shuttle box at the end or ends of the loom at which a magazine is positioned having a plurality of cells, a head motion including at least one pattern chain, means operated by a pattern chain for shifting said shuttle box in normal weaving operation of the loom to bring any one of said cells to race plate level, a weft-detecting mechanism including a feeler shiftable with said shuttle box in a position to enter the top cell of said shuttle box and to engage any weft-carrier which may be positioned in said cell during each beat of the loom in normal weaving operation, indicator mechanism responsive to said weft-detecting mechanism and adapted to initiate a transfer cycle in the next beat of the loom after said feeler engages a substantially exhausted weft-carrier or fails to engage a weft-carrier, means mounting said top cell of said shuttle box for vertical movement relative to the remaining cells in said shuttle box and relative to said feeler to a transfer position to provide a space between said top cell and the uppermost of the remaining cells through which an exhausted weft-carrier may be discharged from the bottom of said top cell, means for moving said top cell to said transfer position in each transfer cycle of the loom, said magazine being mounted in such position that a replacement weft-carrier may be transferred from said magazine to said top cell when said top cell has been moved to said transfer position and a predetermined one of said remaining cells is at race plate level, and means operated by a pattern chain to prevent said indicator mechanism from initiating a transfer cycle in any selected beat of the loom including those beats of the loom in which said predetermined cell is not at race plate level.

8. In an automatic weft-replenishing loom, a vertically shifting shuttle box at each end of the loom, a magazine for reserve weft-carriers at at least one end of the loom, the shifting shuttle box at the end or ends of the loom at which a magazine is positioned having a plurality of cells, a head motion including at least one pattern chain,

means operated by a pattern chain for shifting said shuttle box in normal weaving operation of the loom to bring any one of said cells to race plate level, a weft-detecting mechanism including a feeler shiftable with said shuttle box in a position to enter the top cell of said shuttle box and to engage any weft-carrier which may be positioned in said cell during each beat of the loom in normal weaving operation, indicator mechanism responsive to said weft-detecting mechanism and adapted to initiate a transfer cycle in the next beat of the loom after said feeler engages a substantially exhausted weft-carrier or fails to engage a weft-carrier, means mounting said top cell of said shuttle box for vertical movement relative to the remaining cells in said shuttle box and relative to said feeler to a transfer position to provide a space between said top cell and the uppermost of the remaining cells through which an exhausted weft-carrier may be discharged from the bottom of said top cell, means for moving said cell to said transfer position in each transfer cycle of the loom, said magazine being mounted in such position that a replacement weft carrier may be transferred from said magazine to said top cell when said top cell has been moved to said transfer position and a predetermined one of said remaining cells is at race plate level, means including a hammer in said magazine for transferring a replacement weft-carrier to said top cell, means actuated by said hammer for withdrawing said feeler from the path of the exhausted weft-carrier discharged from said top cell during each transfer cycle of the loom, and means operated by a pattern chain to prevent said indicator mechanism from initiating a transfer cycle in any selected beat of the loom including those beats of the loom in which said predetermined cell is not at race plate level.

9. In an automatic weft-replenishing loom operating with two or more shuttles at least one of said shuttles carrying a weft having a color or other characteristic differing from wefts in the remaining shuttles, a vertically shifting shuttle box at each end of the loom, a magazine for reserve weft-carriers at at least one end of the loom, said magazine or magazines having a total number of cells at least equal to the number of different colors of weft carried by said shuttles, the shifting shuttle box at the end or ends of the loom at which a magazine is positioned having a plurality of cells, a head motion including at least one pattern chain, means operated by a pattern chain for shifting said shuttle box in normal weaving operation of the loom to bring any one of said cells to race plate level, a weft-detecting mechanism including a feeler shiftable with said shuttle box in a position to enter the top cell of said shuttle box and to engage any weft-carrier which may be positioned in said cell during each beat of the loom in normal weaving operation, indicator mechanism responsive in any beat of the loom to said weft-detecting mechanism and adapted to initiate a transfer cycle in the next beat of the loom after said feeler engages a substantially exhausted weft-carrier or fails to engage a weft-carrier, means mounting said top cell of said shuttle box for vertical movement relative to the remaining cells in said shuttle box and relative to said feeler to a transfer position to provide a space between said top cell and the uppermost of the remaining cells through which an exhausted weft-carrier may be discharged from the bottom of said top cell, means for moving said top cell to said transfer position in each transfer cycle of the loom, said magazine being mounted in such position that a replacement weft-carrier may be transferred from said magazine to said top cell when said top cell has been moved to said transfer position and a predetermined one of said remaining cells is at race plate level, and means controlled by a pattern chain for selecting from said magazine a weft-carrier corresponding with the exhausted weft-carrier to be replaced in each transfer cycle of the loom.

10. In an automatic weft-replenishing loom, a ver-

tically shifting shuttle box at each end of the loom, a magazine for reserve weft-carriers at at least one end of the loom, the shifting shuttle box at the end or ends of the loom at which a magazine is positioned having a plurality of cells, a head motion including at least one pattern chain, means operated by a pattern chain for shifting said shuttle box in normal weaving operation of the loom to bring any one of said cells to race plate level, a weft-detecting mechanism including a feeler shiftable with said shuttle box in a position to enter the top cell 10 of said shuttle box and to engage any weft-carrier which may be positioned in said cell during each beat of the loom in normal weaving operation, indicator mechanism responsive in any beat of the loom to said weft-detecting mechanism and adapted to initiate a transfer cycle in 15 the next beat of the loom after said feeler engages a substantially exhausted weft-carrier or fails to engage a weft-carrier, means mounting said top cell of said shuttle box for vertical movement relative to the remaining cells in said shuttle box and relative to said feeler to a transfer position to provide a space between said top cell and the uppermost of the remaining cells through which an exhausted weft-carrier may be discharged from the bottom of said top cell, means for moving said top cell to 20 said transfer position in each transfer cycle of the loom, said magazine being mounted in such position that a replacement weft-carrier may be transferred from said magazine to said top cell when said top cell has been moved to said transfer position and a predetermined one 25 of said remaining cells is at race plate level, means controlled by a pattern chain for selecting from said magazine a weft-carrier corresponding with the exhausted weft-carrier to be replaced in each transfer cycle of the loom, and means operated by a pattern chain to prevent said indicator mechanism from initiating a transfer cycle in 30 any selected beat of the loom including those beats of the loom in which said predetermined cell is not at race plate level.

11. In an automatic weft-replenishing loom having a head motion including at least one pattern chain, said loom operating with two or more shuttles operative in any sequence including sequences in which each shuttle is active for but one pick at a time, at least one of said shuttles carrying a weft having a color or other characteristic differing from wefts in the remaining shuttles, the combination of a shifting shuttle box at each end of the loom, a magazine for reserve weft-carriers at at least one end of the loom, said magazine or magazines having a total number of cells at least equal to the number of different colors of weft carried by said shuttles, a weft-detecting mechanism including a feeler engageable with a weft-carrier resting in one of said shuttle boxes in any beat of the loom, indicator mechanism responsive to said weft-detecting mechanism and adapted to initiate a transfer cycle in any beat of the loom after said feeler engages an exhausted weft-carrier, means controlled by a pattern chain for selecting from said magazine a reserve weft-carrier corresponding in color with the exhausted weft-carrier engaged by said feeler, and means controlled by a pattern chain to prevent said indicator mechanism from initiating a transfer cycle in any selected beat of the loom.

12. In an automatic weft-replenishing loom having a head motion including at least one pattern chain, said loom operating with two or more shuttles, at least one of said shuttles carrying a weft having a color or other characteristic differing from wefts in the remaining shuttles, the combination of a shifting shuttle box at each end of the loom, at least one magazine for reserve weft-carriers having a total number of cells at least equal to the number of different colors of weft carried by said shuttles, a weft-detecting mechanism including a feeler engageable with a weft-carrier resting in one of said shuttle boxes in every beat of the loom, means responsive to said weft-detecting mechanism and adapted to initiate

a transfer cycle in the next beat of the loom after said feeler engages an exhausted weft-carrier, a first vibrator in said head motion, means on a pattern chain for moving said first vibrator into a plurality of positions equal in number to the number of different colors of weft carried by said shuttles, means responsive to the positioning of said first vibrator and operative in each transfer cycle for selecting from said magazine a reserve weft-carrier corresponding in color with said exhausted weft-carrier, a second vibrator in said head motion, means on a pattern chain for moving said second vibrator into a plurality of positions, and means responsive to the positioning of said second vibrator for preventing initiation of a transfer cycle in any selected beat of the loom.

13. In a shuttle box for looms, the combination of at least two shuttle-receiving cells having substantially identical interior dimensions, said cells being stacked vertically, means carried by said shuttle box for mounting the uppermost cell for vertical movement relative to the next cell therebeneath, said last-named means comprising slideable connections between said uppermost cell and the cell therebeneath, latch means for securing said uppermost cell in a position closely adjacent the cell therebeneath and in which all of said cells may be used in a weaving operation, and means for releasing said latch means and for moving said uppermost cell vertically away from the cell therebeneath for a distance approximately equal to the individual vertical dimensions of each of said cells whereby to provide a space beneath said uppermost cell through which an exhausted weft-carrier may be discharged.

14. In a shuttle box for looms, the combination of at least two shuttle-receiving cells having substantially identical interior dimensions, said cells being stacked vertically, means carried by said shuttle box for mounting the uppermost cell for vertical movement relative to the next cell therebeneath, said last-named means comprising slideable connections between said uppermost cell and the cell therebeneath, latch means for securing said uppermost cell in a position closely adjacent the cell therebeneath and in which all of said cells may be used in a weaving operation, means for releasing said latch means and for moving said uppermost cell vertically away from the cell therebeneath for a distance approximately equal to the individual vertical dimensions of each of said cells whereby to provide a space beneath said uppermost cell through which an exhausted weft-carrier may be discharged, and means interposed between said uppermost cell and the cell therebeneath for deflecting a discharged weft-carrier in a generally horizontal direction out of said space.

15. In a shuttle box for looms, the combination of at least two shuttle-receiving cells having substantially identical interior dimensions, said cells being stacked vertically, means carried by said shuttle box for mounting the uppermost cell for vertical movement relative to the next cell therebeneath, said last-named means comprising slideable connections between said uppermost cell and the cell therebeneath, latch means for securing said uppermost cell in a position closely adjacent the cell therebeneath and in which all of said cells may be used in a weaving operation, means for releasing said latch means and for moving said uppermost cell vertically away from the cell therebeneath for a distance approximately equal to the individual vertical dimensions of each of said cells whereby to provide a space beneath said uppermost cell through which an exhausted weft-carrier may be discharged, a plate mounted between said uppermost cell and the cell therebeneath, said plate being pivoted along a horizontal axis so as to lie substantially flatwise between said cells when said uppermost cell is latched in weaving position and lie substantially diagonally of the space between said cells when said uppermost cell is moved away from the cell therebeneath.

16. In an automatic weft-replenishing loom the com-

bination of a vertically shiftable shuttle box having at least two vertically stacked shuttle-receiving cells, means for shifting said shuttle box vertically to position any one of said cells at race plate level, means carried by said shuttle box for mounting the uppermost cell for vertical movement relative to the next cell therebeneath, said last named means comprising slidable connections between said uppermost cell and the cell therebeneath, latch means for securing said uppermost cell in a weaving position closely adjacent the cell therebeneath, and means for releasing said latch and for moving said uppermost cell vertically away from the cell therebeneath into a transfer position to provide a space beneath said uppermost cell through which an exhausted weft-carrier may be discharged.

17. In an automatic weft-replenishing loom the combination of a vertically shiftable shuttle box having at least two vertically stacked shuttle-receiving cells, means for shifting said shuttle box vertically to position any one of said cells at race plate level, means carried by said shuttle box for mounting the uppermost cell for vertical movement relative to the next cell therebeneath, said last-named means comprising slidable connections between said uppermost cell and the cell therebeneath, latch means for securing said uppermost cell in a weaving position closely adjacent the cell therebeneath, means for releasing said latch and for moving said uppermost cell vertically away from the cell therebeneath into a transfer position to provide a space beneath said uppermost cell through which an exhausted weft-carrier may be discharged, and means interposed between said uppermost cell and the cell therebeneath for deflecting a discharged weft-carrier from said space. 25 30

18. In an automatic weft-replenishing loom the combination of a vertically shiftable shuttle box having at least two vertically stacked shuttle receiving cells, means for shifting said shuttle box vertically to position any one of said cells at race plate level, means carried by said shuttle box for mounting the uppermost cell for vertical movement relative to the next cell therebeneath, said last-named means comprising slidable connections between said uppermost cell and the cell therebeneath, latch means for securing said uppermost cell in a weaving position closely adjacent the cell therebeneath, means for releasing said latch and for moving said uppermost cell vertically away from the cell therebeneath into a transfer position to provide a space beneath said uppermost cell through which an exhausted weft-carrier may be discharged, and a plate mounted between said uppermost cell and the cell therebeneath, said plate being pivoted along a horizontal axis so as to lie substantially flatwise between said cells in weaving position and lie substantially diagonally of the space between said cells in transfer position to deflect a discharged weft-carrier from said space. 15 20 25
